(57) CLAIM

We claim the ornamental design for a drinking cup, as shown and described.

DESCRIPTION

FIG. 1 is a perspective view of a drinking cup showing one embodiment of our new design;
 FIG. 2 is a front plan view thereof;
 FIG. 3 is a top plan view thereof;
 FIG. 4 is a bottom plan view thereof;
 FIG. 5 is a perspective view of a drinking cup with a lid showing a second embodiment of our new design;
 FIG. 6 is a front plan view thereof;
 FIG. 7 is a right plan view thereof;
 FIG. 8 is a top plan view thereof; and,
 FIG. 9 is a bottom view thereof.
 The broken lines are illustrative only and form no part of the claimed invention.
